(57) **CLAIM**

The ornamental design for a case with openable and closeable integrated document pouch, as shown and described.

DESCRIPTION

FIG. 1 is a side elevational view of a case with openable and closeable integrated document pouch, the opposite side being substantially identical thereto, in its closed condition with integrated document pouches showing my new design. FIG. 2 is an end elevational view, the opposite end being substantially identical thereto;

FIG. 3 is a side elevational view of the case of FIG. 4 in its open condition;

FIG. 4 is an end elevational view of the case of FIG. 3;

FIG. 5 is a bottom plan view of FIG. 4; and,

FIG. 6 is a top plan view of FIG. 4.
